WASHABLE TOILET PUFF

Arthur C. Brucks, New York, N. Y., assignor to
Hopeck Manufacturing Company, New York,
N. Y., a corporation of New Jersey

Application February 6, 1933. Serial No. 655,427

9 Claims. (Cl. 132—78.5)

This invention relates to an actually washable form of the common low-cost three-element type of toilet puff employed by women by dipping it in loose face-powder and then dabbing the puff on the skin to apply the powder thereto, and employed also to wipe and cleanse the skin, all as distinguished from the other or non-sheet type of powder-puff comprising threads of swan's down or the like, pendant radially from a central handle.

Always heretofore the washing of such puff has caused it to lose its agreeable softness in applying it to the face, either to apply powder to, or to cleanse, the skin. In fact, the washing always has caused the puff thereafter, to cause a feeling of actual harshness, as distinguished from the agreeable sensation of softness previous to washing, this having been true to such extent that in preference to washing a used puff, it has been thrown away by those who believed they could afford replacement by a new puff with its clean and soft outer surfaces. Up to the time of the invention hereof, no toilet puff of this thin sheet-fabric type has existed, so far as I know, which was washable in the above sense that the softness of its application-surface continued to exist after washing to clean-surfaced condition; altho the demand for such a washable puff has been so great that the matter has been an unsolved problem for a good many years.

An object of this invention is a washable puff of this thin sheet-fabric type, preferably retaining the same thin, closely woven outer fabric sheets as heretofore, preferably having pile-surfaces, with the pile surface outside, and being preferably so closely woven as to prevent dust and soiled powder particles from passing into the interior of the puff, all as a basis for the novel structure hereof whereby the soiled outer surfaces of the puff can be thoroly washed, scrubbed with soapy water, and cleansed to the satisfaction of the user, without impairment of the ability of the puff thereafter to create the desired and agreeable sensation of softness in application to the face.

The reasons why the prior puffs of this low-cost thin fabric type have not been washable, altho having the same outer fabric-sheets as the new puff, had remained somewhat obscure, but in the tests connected with the present invention which has solved this long-existing problem, these previously obscure reasons have been discovered by me, and are stated hereinafter.

In accordance with the invention, the toilet puff embodying it may, and preferably does, include the same two thin closely-woven fabric-sheets

as before, and preferably closely woven pile-surface fabrics; but instead of inserting between them, the former cut-out cotton-battling disk, or any other material in any form, which shrinks upon air-drying from water-wet condition, such as any form of cotton or wool not pre-shrunk, I place between the fabric sheets an interior means which not only initially puffs them out better than ever before to a condition best adapted to dipping a curved outer surface in the powder and applying it to the face, but which produces the new result of a toilet puff which can be cleansed thoroly from a soiled condition of the outer fabric-surfaces, by any amount of washing by water desired, and repeatedly after successive soilings, and all without reduction of the agreeable softness and without increase of harshness in use, and without any impairment of the original puff-shape.

Of the drawing

Fig. 1 is a diagrammatic view of apparatus and method according to the invention, illustrating the best form of the invention now known to me;

Fig. 2 shows the two thin but closely woven flat fabric disks previous to assembly;

Fig. 3 is a plan of the same two disks after having been assembled and sewn together;

Fig. 4 is an elevation of the toilet puff in process, after it has been turned inside-out from the condition of Fig. 3, with the pile surfaces outside, and in condition for interior processing as in Fig. 1;

Fig. 5 is a section of the puff after completion of the execution of the method of Fig. 1, and

Fig. 6 is an elevation of the completed puff.

Fig. 1 illustrates a manner of using the invention involving blowing between the outer fabric-sheets a loose fibrous mass C, of suitable material and construction as described below, this being the best method of use thus far produced by or known to me. In the first place, the fibers of loose mass C preferably are vegetable fibers of some short-fibered type too short to be used in the production of fabrics, so that in addition to being themselves of low cost, they lend themselves readily to this low cost process of being blown in between the fabric sheets of the puff.

Fig. 1 illustrates the method in operation, a nozzle N of the pipe P from the blower L being introduced into a small opening H between the fabric sheets A, B of the puff, which otherwise are stitched together at S near but not at their edges; or rather, the operator applies the puff in process to nozzle N so that the latter enters such small opening H between the edges

of the fabric disks; a suitable loose mass of the short-fibered material C being introduced into the funnel F, for each puff in process. The cross section of Fig. 5 illustrates the condition of the interior of the product upon completion of execution of the method of Fig. 1, with the full complement of mass C in place,—Fig. 6 showing the exterior of the completed article.

From comparison of Figs. 1 and 5 it can be seen that enough of the fibers C finally are blown in between the initially flat fabric sheets to cause the latter to be substantially but usually not very greatly distended, and that this distension is more or less progressive away from their sewn-together edges, the distension being greater at points remote from the edges, so that a more or less convex somewhat globular or at least convex outside curvature is imparted to the two outer surfaces of the puff, this curvature preferably as shown being abrupt, beginning at the rim, and such abrupt curvature providing a suitable outwardly curved surface adapted to be applied to and take up the loose face-powder and then to apply the powder to the face.

An ordinary open-palmful of the loose short fibers, introduced into the top of funnel or hopper F, at C, is the quantity which produces substantially this desired extent of distension as in Figs. 5-6, for a puff of the ordinary diameter, i. e. about three inches. The funnel or hopper F preferably is so proportioned relative to its bottom opening into blowing-pipe P that the entire open-palmful of the short fibers is not blown in at once, but rather somewhat gradually, even altho rapidly, as successive portions of the loose mass C in F drop by gravity out of the lower opening of F into the path of the air-blast thru pipe C, as from blower L. The blowing in process is continued until the entire charge of short fibers has been transferred into position between sheets A and B, when the predetermined mass C between them, as in Fig. 5, will impart the desired distension and curvature to said sheets, proportioned to the predetermined charge placed in hopper F. In practice, the top opening of hopper F, thru which the open-palmful of short fibers C is dropped, is closed after the hopper has been charged with the fibers and during the blowing operation, as by a cover hinged to the side wall of the hopper near its top. Only a moderate pressure of air, a few pounds, is required to blow the loose short fibers into the interior of the puff, and into a condition of slightly less volume than when completely loose in the open palm of the hand. For example, a hand bellows may be employed to provide the air-pressure, altho plainly it is better to get it from a power operated blower, as at L, Fig. 1. While the fabric-sheets A, B here, as ordinarily used heretofore, are so closely woven as to be practically impervious to loose powder applied to the exterior surface of the puff, nevertheless the moderate air-blast can pass freely from nozzle N, between the two facing fabrics and out thru them between their threads to atmosphere, leaving the yet loose and not highly compacted mass C between the sheets, held in place by the stitch-line S and by the fabric itself from being blown out, and causing the fibers to be distributed in locations whereby the mass C as a whole generally is more or less thinner near the rim of the puff than at locations more remote from stitch-line S, altho there is no objection to a full ball-shape for cases when the puff is not to be carried in a hand-bag or purse as is more generally the case. As

shown, nozzle N may be smaller than hole H, in a case where fabrics A, B are so closely woven as to interpose excessive resistance to even the moderate air-blast. This air pressure may be quite low because it is not necessary to compact very highly the mass C, which may be, and preferably is, yet quite loose after having been blown into place between sheets A and B, altho then sufficiently distending the exterior surface of one or both of the sheets A, B to the convex puff shape as shown in Figs. 5-6. The principal object of this blowing method is to provide a rapid manner, at low cost, of arranging the short fibered mass C in place, in lieu of the more expensive but permissible method of using the fingers to push the mass into place, which is also less efficient because thereby the portions of the mass C are not readily so evenly distributed in the desired loose form between fabric application-sheets A and B. Not only is it usually not desirable to cause the fabric sheets to be distended excessively by the interior means C but on the contrary it is desirable to have said means distributed evenly and rather loosely between the application-sheets, altho in sufficient volume to distend them to puff shape. I have found that the above described moderate blowing method most quickly and cheaply produces said desired results, particularly with the preferred short-fibered material, and that upon completion of execution of such method, the mass of loose fibers of inner material C lies uniformly in place and subsequently continues in place or continues to tend always to return to proper place, owing to its short-fibered nature, so as to produce and permanently maintain the desirably uniform puff curvature in general as shown in Figs. 5-6, or any desired curvature depending upon the amount of the short-fibered material which is faced between the application-sheets; this blowing method being particularly adapted to the short-fibered materials to be described. All that then remains to be done, after completion of the air-blast process, is to close the puff-opening H at its edge as by hand-sewing this short remaining unstitched arc H of the periphery of the puff thru which nozzle N has been inserted during the blowing operation.

The two fabric-sheets A, B, Fig. 2 are of any desired close woven fabric material as heretofore, preferably alike and, previous to washing, preferably having the desirable particularly soft outer pile surface due to the close weaving. In any case, at least one of the sheets should consist of a fabric possessing as usual when the puff is manufactured, the desired soft outer application-surface of the fabric itself, irrespective of interior mass C as a very readily yielding backing for the fabric. The characteristic of the completed article is that the nature of the means C inside the puff is such that it distends the fabric sheets outwardly as above, not only at the time of completion of the blowing process of Fig. 1, and before washing, but that it substantially maintains such distension, or at least holding in desired puff shape, after washing and particularly previous to and during drying of the fabric sheets, for a purpose to be described, this nature of the means C being involved in the truly washable nature of the new puff. For this purpose the nature of the interior means C is such that not only are its short fibers adapted to the above economical blowing in process, and not only that mass C initially distends the application-sheets as above, but that mass C substantially maintains

such distended condition of facial application sheets after cleansing of the puff by washing and during the period of drying of the application sheets after such washing. This new result is contributed to usefully by the loose, resilient character of short-fibered mass C between the fabric sheets which results from the blowing-in process of Fig. 1, as distinguished from the prior relatively compact cut cotton-battling flat disks; but in the best form of the invention, the interior means C possesses a high resiliency (sufficient to maintain the above puff-shape of the application sheets for all purposes, to be described) during drying after washing, even after having been thoroly wetted or even soaked and water-logged as by very thoro scrubbing in soapy water, i. e., by the regular washing preferred by women for any such article which is to be applied to the skin. For I have found that such maintenance of resiliency, and that freedom from shrinkage, felting and matting, are important, not merely in preserving a soft yielding backing for, and preferably adjacent, the inner surfaces of the outer application-sheets, but more particularly in preserving, after washing, the essential softness of the outer surfaces of the fabric sheets themselves as distinguished from and in addition to such yielding backing. That is, I have found that, in order that the softness of the puff shall be preserved, and continue after washing and drying, it is not only necessary for the mass C to retain its yielding character, and its resilient character, after washing of the puff, but that its resilient character (or rather its shape or volume as initially established inside the puff) should be effective at a time during the drying of fabric-sheets A and B after washing, even altho the mass C may lack substantial resiliency while it is in water-soaked or logged condition as the result of thoro washing by repeated scrubbing in water. In other words, I have discovered that among the reasons why prior sheet-puffs were not washable was because the material between the application sheets consisted of fibers which not only were long but, as in the case of cotton or wool, were liable not only to mat or felt during use, but to shrink upon drying after washing, and that such shrinkage permanently impaired the desired softness of the outer surfaces of the application sheets themselves, as distinguished from the yielding backing of the cotton or wool fibers themselves.

In Fig. 2, the surfaces of the fabric sheets A and B which face one another are the pile or other soft surfaces of the fabric which are to constitute the outer powder-applying or skin-cleansing application surfaces of the puff in Fig. 6, as heretofore.

Fig. 3 shows the condition of the puff in process, after the fabric sheets of Fig. 2 have been machine-sewn together in the same face-to-face relations as in Fig. 2. The generally peripheral stitch-line S is somewhat remote from the rims of sheets A and B, and is discontinuous, leaving a small opening or hole H between small arcs of adjacent rims of the two facial application sheets. But this opening is large enough to permit the puff in process in the state shown in Fig. 3, to be turned inside out to the final relations of the sheets shown in Fig. 4 wherein the outer application pile surfaces (when the fabric is a pile-fabric) are the former facing and adjacent surfaces of Figs. 2 and 3. This turning inside-out of course effectively camouflages altho it does not necessarily perfectly conceal, Fig. 4,

the line of machine-stitches S, as heretofore. But hole H in the present invention is not required to be any larger than is necessary to permit of the turning inside-out, because here no flat disk of cotton-battling is to be inserted thru the hole, but only nozzle N of Fig. 1 which may be quite small as shown, for the purpose of blowing in the short fibers C. In Fig. 4, hole H is shown flared open to receive nozzle N. After completion of the process of Fig. 1 as shown in Fig. 5, the hole H is closed by hand-sewing. The process of Fig. 1 constitutes a labor-saving low-cost and rapid method of completing the puff, as contrasted with the prior method of cutting out a cotton-battling disk and inserting it thru hole H, and then inserting the fingers of the hand thru the hole H in order to smooth out the cotton disk flat in place between flat sheets A and B.

In operation of the invention in use, the blown-in interior and only slightly compacted and yet loose mass C of short fibers, in the sufficient volume above stated (about an open-palmful of the loose short-fibered mass for each puff of ordinary size), is sufficient to distend the fabric sheets to puff shape, and hold one or both of them so, not only previous to washing of the puff, but during and after drying, after washing, in that the continuing condition of the shape and volume and resiliency of mass C prevents the fabric sheets A, B from shrinking during drying. The open-palmful before blowing occupies a little less volume inside the puff, after blowing, even altho it is yet loose and not highly compacted.

That which I have found to be of the greatest value toward the production of a washable powder puff, was that a mass of kapok fibers after having become perfectly soaked and water-logged and after having lost substantially all its instantaneous mass resiliency even when reduced to a wring-dry condition, resulting from thoro washing of the puff, not only did not shrink, during subsequent drying thereof, and did not mat or felt under any conditions of use or of washing, but did the exact opposite of either shrinking, matting or felting, i. e. the mass as it dried, had its initial resiliency and volume fully restored, this action of expansion from the small volume of the wring-dry condition being particularly rapid (so rapid as to be plainly visible to the eye) beginning with the time when the soaking wet kapok was wrung to wring-dry condition. Such most rapid rate of expansion does not continue long and does not rapidly carry the mass C inside the puff back to initial volume as manufactured, but is succeeded by a slower rate of expansion for a longer period of time during the rest of the time of drying of mass C, which lower rate continues until all the water has left mass C, at which time the volume and resiliency of the kapok mass as initially established inside the puff are fully restored, so that if the kapok mass be removed from the inside of the puff and from the slight restriction thereby, the mass by itself will resume its initial value as an ordinary open-palmful for a puff of the ordinary diameter of about three inches; that is, when the mass C inside the puff is entirely dry, it presses the fabric application-sheets outward just as when the puff is first manufactured, so that the puff shape is fully restored, and the application sheets are prevented from returning to their flat condition of Fig. 4 (previous to the process of Fig. 1) either during their drying or subsequent to drying. Thus the initial delicately

110
115
120
125
130
135
140
145
150

yielding nature of the mass C is fully restored as a permanently ideal backing for the fabric application sheets, and furthermore, I have found that for the first time the softness of the outer application-surfaces themselves is fully restored after washing and drying, and I believe the reason for this latter very important result to be that the initial volume and resiliency of the mass C are fully restored in ample time before the drying of the fabric sheets. Thus, in air-drying, as the outer atmosphere at ordinary room temperature and humidity absorbs the water from the outer surfaces of the fabric sheets exposed to the outer air, additional water is conducted to such outer fabric-surfaces from the interior of the fabric sheets, and in turn additional water is conducted to such interiors from the interior mass C which is in water-conducting relation to the inner fabric surfaces; so that mass C is fully dried while yet the fabric sheets are wet and before they themselves have become dry or can begin to shrink; that is, before shrinking of A and B has occurred or can occur, the mass C is fully dried and restored to its initial volume and resiliency as originally established inside the puff, so that it again, after its own drying, puffs out the fabric sheets while they yet are wet, so that during their drying they cannot shrink. And I believe that the initial softness of the outer fabric surfaces is preserved by this means of preventing their shrinkage during their own drying. Thus altho the kapok mass is wettable and completely wettable, by washing of the puff, even to a water-logged condition of the kapok mass, and altho the mass C substantially lacks all resiliency when so thoroly wetted, even in the wring-dry condition resulting from hand-wringing the water-logged mass, yet as a mass free of shrinkability, and soft, delicately yieldable and resilient, and free from matting and felting, it is an ideal backing for the shrinkable fabric application-sheets. If the kapok fibers were long enough to be woven into a fabric suitable for sheets A and B, a toilet puff might be made of such unshrinkable sheets, without need of any interior puff-shaping mass C, but I have found that the very shortness of the kapok fibers which prevents them from being woven into a fabric, is the condition which provides the basis for the possibility of the economical blowing process of Fig. 1, so that all the above advantages of interior mass C are utilized in this toilet puff, without need of making any change from prior practice as to the nature of closely woven thin fabric sheets A and B.

The above characteristics of most rapid expansibility and increase of restoration of volume and resiliency of the kapok mass C at the time of commencement of its air-drying from a wring-dry state of the mass, is not the important thing in this toilet puff, but rather the fact that regardless of any rate as rapid as that, of the restoration of the kapok to its original condition inside the puff previous to wetting, such restoration is completed before drying of the fabric application-sheets, for the above reasons that mass C is air-dried previous to the air-drying of the application sheets, and such drying of mass C fully restores its initial condition inside the puff; i. e., even the outer surfaces of the mass of fibers C, in addition to the interior of the mass, are dried before the inner surfaces of application sheets A and B can become dried. Conversely, in the process of washing the puff, since the application sheets A, B necessarily are

thoroly wetted previous to wetting of the outer portions of mass C, and since the dry kapok initially strongly repels water notwithstanding that I have found that it is water-soaked by a thoro washing of the puff, a fairly thoro if not complete scrubbing of the puff in cleansing water, which would cause substantial shrinkage of a mass of cotton or wool fibers even in a loose mass, and a permanent matting of cotton fibers, might not even thoroly wet the interior of the kapok mass C, in which case of incomplete scrubbing of the puff, the total time of drying of the puff as a whole might be greatly reduced. In such a case, however, the entire kapok mass might become wetted by a hand-wringing of the puff to extract excess water from the fabric sheets, so that the degree of thorowness of washing might not make much difference in the total drying time of the puff.

The valuable feature of loose and only slightly compacted mass C in any case as above is that whatever may be the nature of the washing and drying operations on the puff, the mass C always, save temporarily when it is water-soaked, maintains the desired shape and softness of the application surfaces of the puff, restoring them after washing and drying, to the same condition as when the puff was first manufactured, without shrinkage of either application sheets A or B, or mass C itself, notwithstanding that said fabric sheets themselves are shrinkable and would shrink with any shrunk condition of mass C during the drying of sheets A and B; and another valuable feature of mass C is that neither in use nor as the result of washing does it mat or felt and thereby permit shrinkage of the fabric sheets during drying, or their departure at any time from the desirable initial puff shape; and kapok is preferred also for mass C because its characteristic shortness of fibers adapts it to the preferred economical blowing process of Fig. 1.

The kapok may be employed in the process of Fig. 1 in its natural state (but of course with seeds removed), i. e., in its condition after being loosened from the bales in which it is compressed in Java for export to this country. Masses thus loosened from the compact bale-condition are suitable for use in the process of Fig. 1. The quantity of an open-palmful above described refers to such condition of the kapok as loosened from its compressed condition in the bales. While the blowing-in process is preferred, yet when kapok constitutes mass C or at least a substantial proportion thereof, as an element of the washable puff hereof, as is preferred, it operates advantageously as described above, no matter by what method it is inserted between sheets A and B, provided that a proper volume, as above, is introduced to cause mass C to press outward so delicately against sheets A and B as to permit them to yield readily and move inwardly upon application to the facial skin. I have found that it is by means of no greater resiliency of the mass than that, that sheets A and B during their drying are prevented by mass C from relaxing during their drying, to their flat shape of Fig. 4 in which they could shrink during drying so as to impair permanently their initial surface softness. I have not found that there is any upper limit to the mass (quantity) of loose kapok fibers which can be introduced between sheets A and B, i. e., any upper limit to the amount of its outward pressure against said sheets, save that usually it is not desired to impart an excessive

bulge to said sheets; that is, the softness of the kapok mass always is so great as to yield readily to the inward pressure of application to the skin, notwithstanding the high resiliency of this material. And on the other hand the permanent resiliency of this material (when not in water-soaked condition) is so great, and its freedom from matting and felting so complete, that even in a very loose mass C, (altho sufficient to dis-
10 tend sheets A and B to puff shape), it will, after inward pressure by application to the skin, press resiliently outward with sufficient force to re-store the normal puff shape of the sheets. That is, mass C, when dry, before or after washing, al-
15 ways will possess the desirable amounts of soft-ness and of resiliency, and the desired original volume and shape, irrespective of its degree of looseness or relative compactness inside the puff within a wide range thereof, provided that, altho
20 the mass is in general loose, it is in sufficient volume or sufficiently compact to resist the tendency of the fabric application sheets to shrink during drying after washing, such extent of loose-
25 ness being that which as I have found, enables mass C to yield readily to the delicate pressure of application of the puff to the facial skin so as to maintain the ability of the puff to create the demanded pleasing sensation of softness.

In view of the apparently opposed facts (1) that the prevention of shrinkage of the fabric application sheets A, B apparently would re-
30 quire substantial outward pressure by mass C and (2) that mass C in order to create the sen-
sation of softness when applied to the facial skin, apparently should yield very readily to the pres-
35 sure of such application, (of course in coopera-
tion with the softness of the outer surfaces of the application-sheets), it is surprising that the kapok mass C provides exactly the conditions
40 which satisfy both such apparently opposed facts, and I have not been able to discover the reasons for this ideal nature of the kapok mass to any further extent than as above.

The new toilet puff hereof is claimed for all its uses including the treatment, as cleansing, of the skin by anything in which the puff may be dipped, such as the usual loose face-powder, or even water, for the reason that as above the puff hereof is not injured by water, nor, I have found, by any combination of water and soap desired for thoro
45 cleansing of the puff itself, so that the puff may be used with soap and water, if desired, for cleansing the skin. In each case, (1) of use to apply face-powder and subsequent washing of the puff to cleanse it, and (2) to cleanse the skin with water and soap or water or other liquid alone, the above operations of the elements of the puff will be substantially the same as above described; and in either case, as in any washable fibrous
50 materials, the time of air-drying of the water-
60 soaked article, will be reduced greatly by wringing out to a wring-dry state.

This invention conforms with the essential re-
65 quirement of low cost because, as above, the fibers of interior mass C require no treatment of any kind, but only removal in its natural state from its bale of importation and the loosening involved in such removal in preparation for in-
70 troduction between the application-sheets.

70 I claim:

1. The method of making a washable toilet puff of the fabric-sheet type, which consists in inter-
75 posing in the path of an air-blast directed be-
tween the assembled application-sheets, a loose mass of kapok fibers, and continuing such blow-

ing-in operation until a sufficient quantity of the fibers is introduced between the sheets to cause their distension to puff shape.

2. A washable toilet puff of the sheet type, which includes the combination with the shrinkable fabric application-sheets, of means preventing their shrinkage during their drying after wash-
80 ing, which includes kapok fibers between the sheets in mass and volume holding them in puff shape during their drying after washing of the puff.
85

3. A washable toilet puff of the fabric-sheet type, which includes the combination with the fabric application-sheets having initially soft out-side application-surfaces, of kapok fibers between the sheets in a mass and volume holding them in puff shape both initially and during and after drying subsequent to washing, thereby perma-nently maintaining said softness of their exterior application-surfaces.
90

4. A washable toilet puff of the fabric-sheet type, which includes the combination with the application-sheets, of means between and dis-tending them to puff shape, and including kapok fibers causing the mass to hold the sheets in the puff shape as originally manufactured, both dur-ing and after drying of the application-sheets after washing of the puff.
95

5. A washable toilet puff of the fabric-sheet type, which include the combination with the fabric application-sheets, of a mass of kapok fibers between and holding the sheets in puff shape at all times before washing of the puff, and during and after drying of the sheets after wash-ing of the puff.
105

6. A washable toilet puff of the fabric-sheet type, which includes the combination with the fabric application sheets, of a mass of kapok fibers in natural state between said sheets and pressing them outwardly to puff shape before and after washing of the puff.
110

7. A toilet puff which includes a fabric en-
closure consisting of two fabric sheets of which at least one is closely woven and has a soft ex-
terior surface, and kapok fibers inside said en-
closure in sufficient volume to impart a puff shape thereto.
120

8. A toilet puff which includes a fabric en-
closure consisting of two initially flat fabric sheets secured together near their edges, and an en-
closed resilient mass including kapok holding said fabric enclosure in puff shape before and after the wetting of the puff by washing and while the fabric enclosure is drying after washing, and after the drying of the fabric enclosure.
125

9. In a toilet disk, the combination with the two fabric sheets of which at least one has a soft outer surface agreeable in application to the skin but ordinarily impaired in softness by washing of the puff, of means between the two sheets which includes kapok in a volume holding said soft sur-faced sheet in puff shape, permanently before wash-ing of the puff and during drying thereof after washing, thereby permanently maintaining a resilient backing contributing to the softness of the puff and also preserving the softness of said outer application surface itself by preventing shrinkage of said sheet during the drying of the sheet.
